UNITED STATES PATENT OFFICE.

ELMER BELL, OF MOUNT PLEASANT, PENNSYLVANIA, ASSIGNOR TO BRYCE BROTHERS COMPANY, OF MOUNT PLEASANT, PENNSYLVANIA, A CORPORATION OF PENNSYLVANIA.

DESIGN FOR A BEVERAGE MIXER OR SIMILAR ARTICLE.

Application filed June 23, 1923. Serial No. 6,563. Term of patent 14 years.

To all whom it may concern:

Be it known that I, ELMER BELL, a citizen of the United States, residing at Mt. Pleasant, in the county of Westmoreland and State of Pennsylvania, have invented a new, original, and ornamental Design for Beverage Mixers or Similar Articles, of which the following is a specification.

The figure is an elevation of a beverage mixer showing my new design.

I claim:

The ornamental design for a beverage mixer or similar article, substantially as shown.

In testimony whereof, I have hereunto set my hand.

ELMER BELL.
